MINE CAR

Harold E. Abkowitz, New Castle, and Frank H. Freshwater, Pittsburgh, Pa., assignors to Koppel Industrial Car and Equipment Company, Koppel, Pa., a corporation of Pennsylvania

Application April 28, 1934, Serial No. 722,908

7 Claims. (Cl. 105—364)

The invention pertains to the construction of railway cars and more particularly to that type of car employed in the transportation of coal or ore from the source of supply to a point of distribution.

In the case of coal mines the veins of coal usually run beneath the ground at such a distance so as to employ the burrowing of a tunnel. These tunnels or arteries are made of a sectional area slightly larger than the cross sectional area of coal to be mined and are therefore limited as to the distance between the side walls. It is one of the objects of the present invention to construct a car of maximum width in order to increase the capacity of the car.

It is also found in many mines that the vein of coal is rather thin and consequently the head room or ceiling of the arteries are made appreciably low. It is therefore another object of the present invention to construct a mine car of less height than the usual type of mine cars without diminishing the capacity of the car.

Another object of the invention is the provision of the floor of the car close to the rails so as to lower the center of gravity of the car with respect to the rails, thereby imparting a greater amount of stability to the car in addition to increasing the capacity thereof.

Another object of the invention is the provision of a rigid, durable construction.

These and other objects will become apparent to one skilled in the art from the following description.

In the drawings which form a part of the present description, Fig. 1 shows a plan view of the mine car embodying the improvements of the present invention; Fig. 2 shows a part sectional and part side elevational view taken along line 2—2 of the car shown in Fig. 1; Fig. 3 is an end elevation of the car shown in Fig. 2; Fig. 4 is an enlarged cross sectional view taken along the lines 4—4 of Fig. 1 and Fig. 5 is a cross sectional view taken along the lines 5—5 of Fig. 1.

Referring now in detail to the drawings where-in like characters refer to like parts, 1 indicates a mine car having side walls 2, a floor 3, and end walls 4. The side walls 2 are made up of a girder plate 5 and side plate 6 extending substantially the full length of the car body. The girder plate 5 extending in the same vertical plane from the bottom of the car body to a point below the top edge thereof, has the top portion 7 inclined inwardly within the car body and terminating in a vertical flange 8 in spaced relation to the body of the plate 5. Secured

to the indent upper portion of the side girder formed by the inclined portion 7 and vertical flange 8 is a side plate 6, the latter being preferably Z-shaped having a horizontal flange 9 and oppositely disposed vertical flanges 10 and 11. The upwardly directed flange 11 of the side plate 6 lies against and is attached to the flange 8 of the side girder plate by rivets 12. The downwardly extending flange 10, preferably lying in the same vertical plane as the body of the side girder plate 5, is connected thereto as at 13, by means of a weld or any other desirable method. It will be noted that the side plate 6 together with the portion 7 and flange 8 of the side girder plate 5 forms a rigid truss member 15 along the upper edge of the car side 2.

The floor plate 3, extending the full length and across the bottom of the car, lies in the same horizontal plane a slight distance above the tops of the rails. Marginal flanges 14 formed along the outer edge of the plate 3 and inclined upwardly, overlapping the girder plates 5 and connected thereto by means of rivets.

Adjacent the center of the car and extending longitudinally thereof, beyond the end walls 4, 25 are oppositely disposed angular sills 15. These sills are preferably formed of commercially rolled bulb angles having a horizontal inwardly directed flange 16 resting upon and secured to the floor plate 3 and a vertical flange 17 directed within the body of the car. In order to strengthen the sills 15 against compressive forces due to end shocks, cross ties 18 are located preferably at the center line of the axles. These cross ties are preferably formed of angles having a horizontal flange 19 resting upon and secured to the floor plates 3 and a vertical flange 20 which is connected with the vertical flanges 17 of the sills 15.

A pair of spaced angular members 21 resting upon the floor plate 3, adjacent the center line of each axle, extend between the sills 15 and the side girder plate 5 and are connected thereto by angles 22—22. Secured to the angular members 21 intermediate their ends and to the floor plate 45 3 is an angular support 23. Attached to the angular members 21 adjacent the tops thereof and to the angular support 23 are sub-floor plates 24 having an upwardly directed flange 25 abutting and attached to the side girder plate 5. 50 Wheel hoods 26 completing the sub-floor span the space from the angular support 23 to the sill 15. The wheel hoods 26 are formed of a plate having an arched central portion 27 extending within the car body and marginal flanges 28 55

connected to the sub-floor plate 24, spaced angular members 21 and sill 15.

It will be observed from Fig. 4 that gussets 29 functioning as a diagonal brace connecting the side girder 5, sub-floor plate 24 and wheel hoods 26 form a rigid and durable construction. The gussets 29 formed of a plate 30 having opposite vertically disposed flanges 31-32 are connected to the side girder 5 and the side wall 33 of the arched central portion 27 of the wheel hood 26 respectively. The top portion of the flange 31 is directed inwardly and upwardly to a point adjacent the top of the girder plate and is secured to the flange 8 of the girder plate 5 and flange 11 of the side plate 6. The flange 34 of the gusset 29 connects the flanges 31-32 and is secured to the sub-floor plate 24.

The floor plate 3 has apertures 35 directly beneath the wheel hoods 26 and defined inwardly 20 of the car by the support 23, sill 15 and the spaced angular members 21 for the reception of stub axled wheels 36 which are mounted in open bottom bearings 37 secured to the supports 23 and sills 15.

25 The end walls 4, having a reinforcing curled portion 38 along the top edge thereof, extend between and are secured to the side walls 3. The side portions 39 being tapered to allow for clearance between the ends of two such cars 30 coupled together when turning a sharp bend which is frequently found in tracks leading from deposits to the points of distribution. Angular members 40 connect the tapered portions 39 to the floor plate 3 and the members 41 connect 35 the end wall 4 to the floor plate intermediate the sills 15. Reinforcing angles 42 extend substantially the full height of the end wall 4 along the inner face thereof forming a connection between the end wall 4, sills 15, and angular members 40, in addition to reinforcing the end 40 walls adjacent the center of the car.

The composite bumper 43 extending between the sills 15 outwardly of the end wall 4 is supported by the backing angle 44 which abuts the 45 end wall and is connected to the intermediate portion of the end wall and floor member 41. Superimposed upon the bumper and rearwardly of the front face thereof is a channel shaped draft sill 45 extending across the sills 15 and 50 having a lower flange 46 secured to the sills by clips 47. The web 48 of the draft sill abutting the end wall is secured to the end wall 4 and the reinforcing angles 42.

On the longitudinal medial line and at one 55 end of the car a resilient drafting device 49 is positioned in the draft sill 43 and having a portion 50 thereof extending into the body of the car.

Having thus described the invention what we 60 claim as new and desire to secure by Letters Patent is:

1. In a mine car, a side wall comprising a girder plate connecting the end walls and floor of the car, a portion of the girder plate being offset inwardly and then upwardly throughout the length thereof, a Z-shaped side plate connected to said offset, a flange of the side plate being secured to the upwardly directed offset portion of the side girder plate, the remaining flange being secured to the girder plate in the plane of the major portion thereof.

2. In a mine car having end walls and floor, a side wall connecting said end walls and floor, comprising a girder plate having its upper edge portion offset inwardly and upwardly, thence

vertically upwardly, a side plate connecting the end walls and disposed in the offset, a flange on the side plate disposed in the plane of and secured to the vertically disposed portion of the offset and a second flange disposed in the plane 5 of and secured to the girder plate.

3. In a mine car, in combination, side walls, a floor extending from side wall to side wall and secured thereto, spaced longitudinal sills disposed upon the floor and extending beyond each end thereof, axle bearing sills spaced outwardly of the longitudinal sills and upon the floor, wheel openings in said floor adjacent each side of the car, a wheel and stub axle disposed in each opening, said axle being supported in 15 bearings secured to the adjacent bearing and longitudinal sills, wheel hoods above said wheels and axles and secured to said sills, said hoods having a portion extending outwardly to the adjacent side wall, each side wall having its 20 upper portion bent inwardly and upwardly and reinforced by an angular member secured to the side wall, gusset members secured to the side wall and extending between the wheel hood, wheel hood extension and bent portion of the 25 side wall, end walls on said car and buffer members secured to said longitudinal sills outwardly of the end walls.

4. In a mine car, in combination, side walls, a floor extending from side wall to side wall 30 and secured thereto, spaced longitudinal sills disposed upon the floor and extending beyond each end thereof, axle bearing sills spaced outwardly of the longitudinal sills and upon the floor, wheel openings in said floor adjacent each 35 side of the car, a wheel and stub axle disposed in each opening, said axle being supported in bearings secured to the adjacent bearing and longitudinal sills, wheel hoods above said wheels and axles and secured to said sills, said hoods 40 having a portion extending outwardly to the adjacent side wall, each side wall having its upper portion bent inwardly and upwardly and reinforced by an angular member secured to the side wall, gusset members secured to the 45 side wall and extending between the wheel hoods, wheel hood extension and bent portion of the side wall, and end walls secured to said side walls.

5. In a mine car of the character described, 50 in combination, side walls, a bottom extending between the side walls in a single plane, spaced longitudinal sills mounted on the floor, end walls, axle bearing sills mounted on the floor between each longitudinal sill and the adjacent side wall, wheel openings in the floor between said bearing and longitudinal sills, wheeled stub axles disposed in said openings and mounted in bearings secured to the sills, wheel hoods above said wheels and connected 60 to the sills, an inwardly and upwardly offset on the upper portion of each side wall, a reinforcing member secured to each side wall at said offset, and a gusset member secured to each side wall adjacent each wheel hood and extending 65 between the reinforcing member, axle bearing sill and adjacent wheel hood.

6. In a mine car in combination, spaced sills, side walls having the upper portion thereof offset inwardly and upwardly, an angular member disposed in said offset, secured thereto and to said side wall, a floor disposed below said sills, secured thereto and to said side walls, transverse members disposed above said floor and connected to each sill and the adjacent side wall, 75

an axle bearing sill mounted on said floor outwardly of each of said sills and connected to said transverse members, a cover plate connecting said transverse members and bearing sill, a gusset plate secured to each side wall adjacent said angular member and to said cover plate.

5. 7. In a mine car in combination, a floor, end walls disposed above and connected with said floor, side walls disposed above the floor and

connecting said floor and end walls, each side wall having a top reinforcement comprising an inwardly and upwardly offset portion extending between said end walls, and an angular member having one leg secured to said side wall and the other leg secured to the offset portion.
